CLAIM

The ornamental design for eye glasses, as shown and described.

DESCRIPTION

FIG. 1 is a perspective view taken from the top, front and right side of the eye glasses showing my new design in which the right side temple is angled downward and fully extended and the left side temple is fully shortened;

FIG. 2 is a front elevational view of the eye glasses;

FIG. 3 is a rear elevational view thereof;

FIG. 4 is a right side elevational view thereof, the left side view being a mirror image to the right side view;

FIG. 5 is a top plan view thereof; and,

FIG. 6 is a bottom plan view thereof.
